UNITED STATES PATENT OFFICE.

HARRY W. RICHARDS AND VINCENT P. FORD, OF BALTIMORE, MARYLAND.

AUTOMATIC TRAIN-CONTROLLING DEVICE.

1,330,007.

Specification of Letters Patent.

Patented Feb. 3, 1920.

Application filed August 26, 1918. Serial No. 251,485.

To all whom it may concern:

Be it known that we, HARRY W. RICHARDS and VINCENT P. FORD, citizens of the United States, both of Baltimore, State of Maryland, have invented new and useful Improvements in Automatic Train-Controlling Devices, of which the following is a specification, reference being had to the accompanying drawings.

10 An important object of the invention is to provide an improved arrangement of cab mechanism and electric circuits for controlling the air-brakes on a train or vehicle upon a track, to automatically bring the train or 15 vehicle to a stop in times of danger for preventing collisions or other accidents, and to provide a simple, durable and effective device to indicate to the person having control of the movements of the train or vehicle, 20 the presence of another vehicle upon the same track, or some derangement of the track or apparatus that would render it necessary to stop.

Another object of our invention is to provide means for bringing the train to a stop automatically should the person having control of the movements of the train or vehicle fail to obey the signal indications, and to provide means whereby the train or vehicle may be run without interference of the 30 automatic device, so long as it is run according to the cab signal indications.

It is also an object of our invention to provide means whereby the failure to obey 35 signal indications will be recorded, so as to enforce watchfulness on the part of the person having control of the train.

A further object of the invention is to provide means of the above mentioned character which will apply the brakes when its circuit is opened, thus always operating on the safe side should the source of current fail.

In accomplishing the objects stated, we 45 provide stationary mechanism along the trackway adapted to coöperate with movable mechanism on the vehicle, when they come into juxtaposition, to start the operation of the mechanism which is adapted to automatically give a danger indication (either a brake or a signal actuation) and we provide controllable mechanism, magnetic in its operation, for determining whether such started operation shall be allowed to become 55 effective.

Other features of the invention contribut-

ing to the efficiency of the operation, or to the simplicity of construction, are included within this invention and will be hereafter more fully explained.

60 In the accompanying drawings forming a part of this specification and in which like or similar reference characters indicate like or corresponding parts, Figure 1 is a side elevation of our roadway device and coöperating vehicle equipment shown mounted on the truck of some vehicle, as, for example, the locomotive tender; Fig. 2 is an end view of the roadway device and the coöperating vehicle equipment, this view showing a portion of the truck and one of the wheels of the vehicle, the roadway device being in position to operate the "star" wheel 9 on the short shaft of the vehicle equipment; Fig. 3 is also an end view of the roadway device 65 and the coöperating vehicle equipment, this view showing the roadway device in position to operate the "star" wheel 10 on the long shaft of the vehicle equipment; Fig. 4 is a plan of the roadway mechanism, 70 showing top cover removed; Fig. 5 is a side view thereof; Fig. 6 is a diagram showing the preferred location and arrangement of the roadway mechanism; Fig. 7 is a sectional view of the vehicle equipment, being 75 a vertical section through the box shown in Figs. 1, 2 and 3, as mounted on the outer side of the truck; Fig. 8 is a plan of the rotary contact on the end of the short shaft of the vehicle apparatus; Fig. 9 is a vertical section through our brake-applying mechanism; and Fig. 10 is a diagram of the controlling circuits carried on the vehicle.

90 Referring first to Figs. 1 to 4, inclusive, the numeral 1 represents a railway rail supported on the usual ties 2. 3 indicates the vehicle wheels which are shown as mounted on a suitable truck 4, supporting a body 5. Located on the outer side of the rail and 100 extending parallel with it is the electromagnetic trip device 6, which consists of a number of magnet coils mounted in a box, and having trips 7 and 8 mounted on the sides of the magnet box in such a position 105 as to engage the proper "star" wheel of the vehicle apparatus, one after the other.

The roadway apparatus is shown in Figs. 4 and 5. In the plan view, Fig. 4, the appliance is shown with the top cover removed. 110 It is preferred that the magnet coils be mounted on a common yoke and the alter-

nate coils be of different polarity, but they may be mounted in any other suitable manner.

As shown in Fig. 6 there are preferably three of the electromagnetic trip devices at each block entrance, at varying distances from the point at which the stop is to be made, the first or most remote, designated as the "distant", being designed to give a caution indication on the vehicle, is produced by trips on the magnet box which are in position to actuate the "star" wheel 9 on the short shaft of the vehicle apparatus, as shown in Fig. 2; the second, designated as the "approach", being designed to give a stop signal on the vehicle and to cause the automatic application of the brakes if the speed is above a predetermined rate, is produced by trips on the magnet box which are in position to actuate the "star" wheel 10 on the long shaft of the vehicle apparatus, as shown in Fig. 3; and the third, or "home" which will produce a stop if the previous warnings are disregarded, is produced by trips in position to actuate the "star" wheel 9, similar to the "distant" trip shown in Fig. 2.

The diagram, Fig. 6, shows one method of wiring the roadway appliances for protecting the block No. 2. For purpose of illustration we may suppose the track shown to be used for east and west bound traffic. The roadway appliances for controlling east bound movements may be located in the adjacent block No. 1, and those for west bound movements in the adjacent block No. 3. The blocks being formed by the insulated joints 11 in the track rails. Each adjacent block is equipped with track appliances located in the block ahead and back, as shown for the block No. 3.

The relay 12 at one end of the block is energized by the track battery 13 at the opposite end of the block, and is adapted to be shunt by the wheels and axles of the vehicle on the track rails, so the relay will be deenergized while there is a train or vehicle in the block. A contact on the relay when energized connects the battery 14 to the roadside appliances in the blocks No. 1 and No. 3, the current returning to the battery through a common wire. Thus, the magnet coils in the roadside appliances will be energized when the block ahead is clear. The roadway appliances may be wired in any other manner which will give the required results.

A sectional front view of the vehicle apparatus is shown in Fig. 7. The device performs two functions, one of which, mechanical in its action, consists in engaging the track trips and breaking the vehicle circuit, and the other, magnetic in its operation, holds the vehicle apparatus in a predetermined position while passing over an ener-

gized track magnet. The mechanical contact part consists of two "star" wheels, rigidly attached to shafts extending inward transversely to the longitudinal axis of the vehicle and carrying cams on their inner end. The two wheels have different length shafts so that their teeth will engage with the proper roadside trip. In order to keep the wheels from "spinning" when struck, each shaft is provided with disks 16 and 17, having teeth that are forced together by a spring 18, but will permit the disks to slide by one another if sufficient force is applied. The disk 16 is rigidly attached to the case of the mechanism and remains stationary when the shaft is turned, while the disk 17 is arranged to revolve with the shaft and also to slide horizontally against the spring 18 on a sliding keyway. The number of teeth on the disks corresponds to the number of teeth on the "star" wheel and it is arranged that the teeth are forced apart, against the spring 18, by the motion of the shaft when the "star" wheel engages a roadside trip, and when the shaft is turned sufficiently to operate the mechanism the teeth are again pushed into mesh by the spring 18, so as to check any further motion of the shaft until the next roadside trip is engaged. The magnetic part of the vehicle apparatus consists of an armature 19, normally in a horizontal position and so situated as to be within the field of the track magnets over which it may be passing. An upwardly projecting arm 20 on the armature 19 connects with one arm of the adjustable lever 21, whose horizontal arm engages a spring operated plunger 22 that holds the contact springs closed when the armature is pulled down by passing through the field of a track magnet. Another lever 26 has one arm held in contact with the cam 15 on the "star" wheel shaft, while on the other end is formed a latch to hold up the arm of the armature lever 21, and thus maintain the contact closed. The shorter shaft also carries additional rotary contacts 25 which are normally closed. This rotary contact is used to produce the "home" or stop indication, and a plan view is shown in Fig. 8. Each of the "star" wheel shafts are provided with a similar equipment, an armature 19, levers 21 and 26, cam 15, etc. The cam 15 has three active portions, any one of which when brought under the end of the lever 26 will raise that end of the lever and cause the hook end to move out from under and release the armature lever 21, as shown in the dotted lines. It is arranged that when the mechanism is in the normal or "running" position as shown in Fig. 7, a low or inactive portion of the cam 15 is under the end of the lever 26, and the hook on the other end of lever 26 holds up the arm of the armature lever 21. Also, when the mechanism is in this position one of the contact

points 25, as shown in Fig. 8, are closed, so that the current may pass from one of the binding posts through the contact 25 to the other binding post. When the "star" wheel 5 engages the first trip 7, Figs. 1 and 4, the "star" wheel will be turned one-sixth of a revolution, or until the next tooth of the "star" wheel is moved to the normal position of the one that had engaged the trip, and 10 this partial revolution of the shaft brings an active portion of the cam 15 under the end of the lever 26, and also opens the contact 25. This active portion of the cam 15 lifts the end of the lever 26 which moves it 15 to the position shown in dotted lines, and thus unlatches the armature lever 21, which will drop and open the circuit unless at that moment the armature passes through the field of an energized track magnet. When 20 the "star" wheel engages the second trip 8, Figs. 1 and 4, the shaft is again turned one-sixth of a revolution, and this partial revolution brings the next or inactive portion of the cam 15 under the end of lever 26, allowing 25 lever 26 to return to its normal position, and also bringing the next contact section in position to close the contact 25. Thus there are two operations of the "star" wheel at each indication point; the first operation, 30 caused by engaging the trip 7, moves the cam 15 in position to release the armature lever 21, and the second, caused by engaging the trip 8, moves an inactive portion of the cam 15 under the end of the lever 26 so as to 35 return the mechanism to its normal position. The whole apparatus is mounted in a box and one is mounted on each side of the vehicle.

The air control device shown in Fig. 40 9 consists of an electro-magnet 28, which when energized, opens a passage from the main reservoir through the valve 29 to the chamber 30 above a piston 31, which, in addition, is held down by a spring 32. This 45 in turn holds down a larger piston 33, which seats a valve 34, closing the train line to the atmosphere. All chambers not normally under pressure are vented to the atmosphere to take away any leakage past the 50 valves. There is also a connection from the main reservoir through the electro-pneumatic valve 29 to the under side of a piston 35 of a "non-release" valve which thus holds open a valve 36 connecting the main reservoir with the engineer's brake valve. When 55 the electromagnet 28 is deenergized the valve 29 will be closed, cutting off the main reservoir air from above the piston 31 and from the "non-release" valve. This permits the 60 pressure in the train line or brake pipe to open the valve 34, which vents it to the atmosphere through the vent hole 37, and also exhausts the air from under the piston 35 of the "non-release" valve, closing the valve 65 36, thus applying the brakes, and at the same

time preventing the engineer from taking any more air from the main reservoir to release them. A contact 38 under the magnet armature 39 is opened when the magnet is deenergized so that the magnet can only 70 be reenergized by current supplied direct through the coil. When sufficient air has exhausted from the brake pipe to cause the brakes to set, the spring 32 moves the valve 33 downward, and when the piston 33 moves 75 far enough to uncover the hole 40 in the bushing, air from chamber 30 passes through the hole 40, and as the air can pass through the hole 40 faster than it can escape through the smaller hole 41, the pressure will build 80 up over the piston 33 and force the valve 34 closed. The reduction of air pressure made by the device is regulated by the spring 32, which is adjusted by the nut 42, and the greater the pressure of the spring 85 32 the less will be the reduction made.

A diagram of the vehicle circuits is shown in Fig. 10. The speed control mechanism shown is of the centrifugal ball type and is geared to an axle. The arm 45 is raised as 90 the speed increases, rotating a vertical shaft by means of bevel gears which carries contact arms 46 and 47. The contact 46 is closed just before the contact 47 is opened by the increasing speed. Any suitable design of speed control mechanism may be used to perform these functions. The purpose of the reversing switch is to throw the circuits of the apparatus on one side of the vehicle to the apparatus on the other when 100 the vehicle is reversed. The cab signals may consist of green, yellow and red lights and a bell, connected with the proper circuits. The relay 48 is controlled by a circuit from the battery 50, through conductors 105 62, 63, 64 and 65, through the contact 23 on the short shaft of the vehicle apparatus, controlled by the "distant" trips, through conductor 66, through contact of the reversing switch, and conductor 67 to the coils 110 of the relay 48, returning by the common return wire to battery 50. A circuit from battery 50, through conductors 62 and 68, contact 51 on relay 48, conductor 69, through the light and back to battery 50, illuminates 115 the green or "clear" signal light. The other relay 49 is controlled by a circuit from the battery 50, through conductors 62, 63, 64 and 65, through the contact 24 on the long shaft of the vehicle apparatus, operated by the 120 "approach" trips, conductor 70, the contact of the reversing switch, conductor 71, through the coils of relay 49, and back to battery 50. A circuit from the battery 50, through conductors 62 and 68, through the 125 contact 53 on relay 49, conductors 72, 73 and 74, through contact 38, conductor 75 and the coil of the air device, and back to battery 50, is the main vehicle or "holding" circuit. A circuit from battery 50, through conduct- 130

- tors 62 and 68, contact 52 on relay 48, conductor 76, contact 54 on relay 49, conductor 77, through the light and back to battery 50, illuminates the yellow or "caution" signal, 5 and a branch of this circuit from contact 52 on relay 48, through conductor 78, contact 46 of the speed control mechanism, conductor 79, through the bell and back to battery 50, rings the bell if the speed is too high. The 10 red light or "stop" signal is illuminated by a circuit from battery 50, through conductors 62 and 68, contact 55 on relay 49, conductor 80, through the lamp and back to battery 50.
- 15 A circuit from battery 50, through conductors 62, 63 and 81, contact 47 of the speed control mechanism, conductors 82 and 93, the contact of the reversing switch, conductor 94, through the rotary contact 20 25, conductors 95; 96, 73, and 74, contact 38, conductor 75, the coils of the air device and back to battery 50, permits the air device to be maintained energized after the relay 49 is deenergized, provided that the contact 47 is not opened by excessive speed, or 25 the rotary contact 25 is not opened by engaging a "home" trip.
- A circuit from the battery 50, through conductors 62, 63 and 81, contact 47 of the speed 30 control mechanism, which is only closed at low speed, conductors 82 and 83, through key 56, conductors 84 and 75, through the coil of the air device and back to battery 50, permits the air device to be energized by 35 pressing the key 56, which is preferably sealed in the open position, so that the breaking of the seal to operate this key will record the failure of the engineer to run according to the signal indications.
- 40 Another circuit provides means for entering an occupied block at low speed by the operation of the special key 57, which picks up a "stick" relay 58, the relay 58 being energized by a circuit from battery 50, through 45 conductors 62, 63 and 81, contact 47 on the speed control mechanism which is only closed at low speed, through conductors 82, 83 and 85, key 57, conductor 92, through the coils of relay 58 and back to battery 50.
- 50 The relay 58 being energized closes contacts which remain closed as long as the speed is low, and current from conductor 85 passes through contact 86, conductor 89, the coils of relay 58, and back to battery 50, so as to form 55 a stick circuit. Current from conductor 85 passes through contact 57, conductors 90 and 74, contact 38, conductor 75 and the coil of the air device, back to battery 50, energizes the air control device. The current in conductor 85 also passes through contact 88 on 60 relay 58, conductors 91 and 77, through the yellow light and back to battery 50, illuminates a "caution" signal.
- The negative side of battery 50 may be 65 grounded to the vehicle, as shown at 59,

so that should a wire become crossed or grounded it will shunt battery 50 and protect against dangerous failures.

When the block ahead is occupied, the track magnet coils at the "distant", "approach" and "home" indication points in the adjacent block will be deenergized, and when the apparatus on the following train engages the "distant" trips contact 23 will be opened, deenergizing relay 48, which extinguishes the green light and illuminates the yellow. If the speed be too high the contact 46 on the speed control mechanism will be closed, causing the bell to ring. There is no automatic application of the 80 brakes at this point, and the cab signal only is given. This indication requires that the engineer or person having control of the train or vehicle reduce the speed of the train to a predetermined rate by the time the vehicle 85 engages the "approach" trips. When the "approach" trips are engaged the contact 24 will be opened, deenergizing relay 49, which extinguishes the yellow light, illuminates the red one, and the contact 53 90 being open cuts off the current in conductors 72, 73, 74 and the air control device. If the speed of the vehicle has been reduced to the prescribed rate the contact 47 on the speed 95 control mechanism will be closed, and a circuit from battery 50, through conductors 62, 63 and 81, contact 47, conductors 82 and 93, the contact on the reversing switch, conductor 94, rotary contact 25, conductors 95, 96, 73 and 74, contact 38, conductor 75, 100 through the coil of the air device, and back to battery 50, maintains the air device energized so as to avoid the automatic brake application. If, when the "approach" trips are engaged the speed of the vehicle is too 105 high contact 47 of the speed control mechanism will be open, and when relay 49 is deenergized there will be no current from either source to energize the air control device, and the brakes will be applied automatically in addition to displaying the red signal light. The red signal light received at the "approach" indication point requires that the vehicle be stopped by the engineer before the "home" trips are engaged. If, 115 after receiving the red signal in the cab, the train should exceed the prescribed rate of speed the contact 47 will open, causing the air device to deenergize and apply the brakes. Should the "home" trips be engaged the contact 25 will be opened, and this contact 25 being connected in series with the contact 47 of the speed control mechanism will also cause the brakes to be applied 120 when the "home" trips are engaged.

Should the block ahead be clear the track magnet coils at the indication points will be energized, and the contacts 23 and 24 will not be opened, and the train will pass over the track apparatus without being stopped. 125 130

It is to be understood that the form of our invention herewith shown and described is to be taken as a preferred example of the same and that certain changes in the shape, size and arrangement of parts may be resorted to without departing from the spirit of the invention or the scope of the subjoined claims.

Having thus described our invention, we claim:

1. In a train controlling device, the combination of a stationary mechanical trip on the roadbed, an electro-magnet on the roadbed adjacent thereto, means for energizing the electro-magnet when the block ahead is clear, a train stopping means carried on the vehicle including a closed electric control circuit, a normally closed circuit breaker in said circuit, an armature connected with the normally closed circuit breaker and arranged to be attracted by the magnet on the roadbed, and means on the vehicle for holding the armature in position to keep said circuit breaker closed, and mechanically operated means on the vehicle for releasing said holding means to permit the armature to open said circuit breaker, said releasing means arranged to be operated by engaging the stationary trip on the roadbed.
2. In a train controlling device, the combination of a stationary mechanical trip on the roadbed, an electro-magnet on the roadbed adjacent thereto, means for energizing the electro-magnet when the block ahead is clear, a train stopping means carried on the vehicle, a closed electric control circuit, an electro-magnet for holding inoperative the train stopping means, said magnet included in said control circuit, a normally closed circuit breaker in said circuit and an armature connected with the normally closed circuit breaker and arranged to be attracted by the magnet on the roadbed, means on the

vehicle for holding the armature in position to keep said circuit breaker closed, and mechanically operated means on the vehicle for releasing said holding means to permit the armature to open said circuit breaker, said releasing means arranged to be operated by engaging the stationary trip on the roadbed.

3. In a train controlling device, the combination of a stationary mechanical trip on the roadbed, an electro-magnet on the roadbed adjacent thereto, a train stopping means carried by the vehicle, a closed electric control circuit, an electro-magnet for holding inoperative the train stopping means, said magnet included in said control circuit, a normally closed circuit breaker in said circuit, an armature connected with the normally closed circuit breaker and arranged to be attracted by the magnet on the roadbed, means on the vehicle for holding the armature in position to keep said circuit breaker closed, mechanically operated means on the vehicle for releasing said holding means to permit the armature to open said circuit breaker, said releasing means arranged to be operated by engaging the stationary trip on the roadbed, and a second control circuit on the vehicle including contacts operated by a speed control device and in series with a second mechanically operated circuit breaker, and adapted to maintain the train stopping means inoperative when the speed of the vehicle is low.

In testimony whereof, we hereunto affix our signatures in the presence of two witnesses.

HARRY W. RICHARDS.
VINCENT P. FORD.
